(57) **ABSTRACT**

A woven fabric for use in a machine to produce a fiber web, such as a tissue fiber web, has a paper side formed by interwoven warp yarns and weft yarns. The paper side has a plurality of twill lines formed by neighboring floatations of warp yarns. The twill lines have an MD vector component in a machine direction and a CD vector component in a cross machine direction. At least some twill lines are diagonal, with a CD vector component being unequal to zero. The diagonal twill lines include first diagonal twill lines with CD vector components that have an opposite sign to the CD vector components of second diagonal twill lines. A sum of all CD vector components of the first diagonal twill lines is substantially balanced with a sum of all CD vector components of the second diagonal twill lines.

WOVEN STRUCTURED FABRIC WITH
CROSSING TWILL LINESCROSS-REFERENCE TO RELATED
APPLICATION

This application is a continuation, under 35 U.S.C. § 120, of copending International Patent Application PCT/EP2021/081774, filed Nov. 16, 2021, which designated the United States; this application also claims the priority of prior U.S. patent application Ser. No. 17/101,151, filed Nov. 23, 2020, and Ser. No. 17/172,681, filed Feb. 10, 2021; the prior applications are herewith incorporated by reference in their entirety.

FIELD AND BACKGROUND OF THE
INVENTION

The invention concerns a woven fabric for use in a machine to produce a fiber web, preferably a tissue fiber web, the woven fabric having a machine direction and a cross machine direction, as well as a paper side and a machine side. The paper side is formed by warp yarns and by weft yarns which warp yarns and weft yarns are interwoven with each other. The paper side comprises a plurality of twill lines, each twill line being formed by a plurality of neighboring floatations of warp yarns. The twill lines comprise an MD vector component directed in the machine direction of the woven fabric and a CD vector component directed in the cross machine direction of the woven fabric. At least some twill lines are diagonal twill lines meaning that the CD vector component of these twill lines is unequal to zero.

Such woven fabrics are already known in the market. One example of such a fabric is shown in FIG. 1 which illustrates a view on of the paper side of the fabric 10'. As can be seen the paper side is formed by a plurality of warp yarns interwoven with a plurality of weft yarns. For the sake of clarity only three warp yarns are provided with reference signs, namely WA1', WA2' and WA3', and only five weft yarns are provided with reference signs, namely WE1', WE2', WE3', WE4' and WE5'. The fabric is flat woven which means that the warp yarns extend substantially, but not necessarily exactly, in machine direction MD of the woven fabric 10', whereas the weft yarns extend in cross machine direction CD of the woven fabric 10'. The woven fabric 10' is made endless by a not shown seam. In case the fabric is not flat woven but round woven the warp yarns would correspond to the weft yarns and vice versa.

In the shown example from the prior art each warp yarn forms several floatations on the paper side of the woven fabric 10', wherein all floatations have the same length. One of these floatations is denominated with reference sign FL' in FIG. 1. This flotation FL' is formed by warp yarn WA2' which floats above the five weft yarns WE1'-WE5'. The neighboring warp yarns WA1' and WA3' form similar floatations on the paper side of the woven fabric 10' but with an offset. Thus, warp yarn WA1' floats only above weft yarns WE4' and WE5'—and three further weft yarns without reference sign—but not about weft yarns WE1', WE2' and WE3'. The offset results in that directly neighboring floatations of warp yarns together form a diagonal twill line TL' that extends substantially from the lower right side to the upper left side in FIG. 1. In fact, several such twill lines extend parallel to each other across the complete paper side of the woven fabric 10'. The distinctive diagonal twill lines are clearly separated from each other. In the present example between

two neighboring twill lines there is some kind of plain weave structure, i.e. a woven structure which is free of any floatations. For the sake of clarity, it should be mentioned that the word “floatation” means that a yarn floats about at least two other yarns that are located next to each other.

The diagonal twill lines form a certain angle with the machine direction MD of the woven fabric 10', which angle is not zero. If the direction of the twill line TL' is described by an MD vector component MD-VC' extending in the machine direction MD of the woven fabric 10' and an CD vector component CD-VC' extending in the cross machine direction CD of the woven fabric 10', this means that the value of the CD vector component CD-VC' is unequal to zero. In the present example the CD vector component CD-VC' is directed against the cross machine direction CD of the woven fabric 10' so that it has a negative sign. The ratio of the MD vector component MD-VC' and the CD vector component CD-VC' is characteristic for the angle formed by the diagonal twill line TL' with the machine direction MD of the woven fabric 10'.

Such a woven fabric with diagonal twill lines on its paper side is conducive to sheet building, especially when the sheet is transferred to it with a rush speed differential. However, the strong diagonal twill lines make the fabric directional and difficult to guide on the paper machine.

SUMMARY OF THE INVENTION

It is an object of the present invention to avoid or at least 30 reduce this problem. In particular the present invention aims to provide a woven fabric that is conducive to sheet building while at the same time it is easy to guide on the paper machine. At the same time the pattern that is imparted by the woven fabric to the fiber web should be better controlled.

With the above and other objects in view there is provided, in accordance with the invention, a woven fabric for use in a machine for producing a fiber web, the woven fabric, the woven fabric comprising:

a multiplicity of mutually interwoven warp yarns and weft 40
yarns forming a paper side of the woven fabric;
said paper side having a plurality of twill lines each being
formed by a plurality of neighboring floatations of said
warp yarns;

said twill lines having an MD vector component directed
in a machine direction of the woven fabric and a CD
vector component directed in a cross machine direction
of the woven fabric;

at least some of said twill lines being diagonal twill lines
having a CD vector component that is unequal to zero;
a plurality of said diagonal twill lines consisting of first
diagonal twill lines and second diagonal twill lines,
wherein the CD vector components of the first diagonal
twill lines have an opposite sign to the CD vector
components of the second diagonal twill lines;
a sum of all CD vector components of said first diagonal
twill lines being substantially balanced with a sum of
all CD vector components of said second diagonal twill
lines;

said weft yarns that are located in a middle of any one of
said floatations that define said diagonal twill lines
having a cross section which is smaller than a cross
sections of the remaining said weft yarns that are not
located in the middle of any one of said floatations that
define said diagonal twill lines.

In other words, the above and other problems associated with the prior art are solved by the generic woven fabric as described at the beginning wherein the plurality of diagonal

twill lines consists of first diagonal twill lines and second diagonal twill lines, wherein the CD vector components of the first diagonal twill lines have an opposite sign to the CD vector components of the second diagonal twill lines, and wherein the sum of all CD vector components of the first diagonal twill lines is substantially balanced with the sum of all CD vector components of the second diagonal twill lines.

In this context the term "substantially balanced" means that the absolute value of the CD vector components of all first diagonal twill lines taken together corresponds to between 80% and 120%, preferably to between 90% and 110%, most preferably to 100%, of the absolute value of the CD vector components of all second diagonal twill lines taken together.

Having diagonal twill lines extending in different directions on the paper side of the woven fabrics allows to guide the woven fabric easily on the paper machine.

In a preferred embodiment the woven fabric has only one layer. In such a case the warp and weft yarns that form the paper side at the same time also form the machine side of the woven fabric.

According to a preferred embodiment the number of the first diagonal twill lines substantially equals the number of the second diagonal twill lines. Furthermore, a total length of all first diagonal twill lines may substantially equal the total length of all second diagonal twill lines.

The first diagonal twill lines preferably have all the same first CD vector component and the second diagonal twill lines preferably also have all the same second CD vector component. More preferably, the first CD vector component has the same absolute value as the second CD vector component. This can result in some kind of symmetry of the first diagonal twill lines and the second diagonal twill lines with respect to the machine direction MD of the woven fabric. This is especially true if, in addition, all diagonal twill lines have the same MD vector component.

Preferably the diagonal twill lines are formed from neighboring floatations of warp yarns, wherein the floatations have a length of at least 3, more preferably of 5. A "length of at least 3" means that the respective warp yarn floats over at least three consecutive crossing yarns. A length of 5 means that the yarn floats over 5 yarns.

In an advantageous embodiment, some of the weft yarns have a different cross section than other weft yarns. For example the cross sections can vary as to their shape. However, additionally or alternatively these weft yarns can differ from the other weft yarns with respect to their material and/or type. The term "type" means that the weft yarns are either monofilaments or multifilaments.

According to the present invention the weft yarns that are situated in the middle of any one of the floatations that define the diagonal twill lines have a cross section which is smaller than the cross sections of the remaining weft yarns that are not situated in the middle of any one of the floatations that define the diagonal twill lines. With such a configuration of different cross sections of the weft yarns, it is possible to keep the knuckle height of the floatations relatively low, i.e., to control the knuckle height of the floatations.

Preferably the warp yarns which form with their floatations the diagonal twill lines are interwoven with the weft yarns in a plain weave structure between two successive floatations. In other words the corresponding sections of the warp yarns are interwoven with the weft yarns in such a way that the warp yarn goes continuously above and below directly neighboring weft yarns.

To achieve a more straight and less "stepped" twill line, it is advantageous if the floatations of the warp yarns which

define the diagonal twill lines themselves form an angle unequal to 0° with the machine direction of the woven fabric, wherein the sign of the angle corresponds to the sign of the MD vector component of the diagonal twill line that is formed by the corresponding flotation.

In a preferred embodiment at least some of the diagonal twill lines extend straight from one side of the woven fabric to the opposite side thereof. Additionally or alternatively at least some of the diagonal twill lines can end somewhere between opposite sides of the woven fabric. With "sides" of the fabric are meant the left and the right side of the fabric when looking into machine direction of the fabric.

Some diagonal twill lines can be broader than other diagonal twill lines. A broader twill line can be achieved for example by having two or more twill lines directly next to each other, i.e., without any separation e.g. a separation formed by a plain weave structure between them. Then these two or more twill lines can jointly form one broader twill line.

In some embodiments of the present invention the diagonal twill lines can be formed from neighboring floatations of warp yarns, wherein the floatations have a length of 7 or even more.

To obtain a desired level of contact area on the paper side of the fabric without removing excessive amounts of warp yarn material, it is proposed that the weft yarns that are situated in the middle of any one of the floatations that define the diagonal twill lines pass over at least one adjacent warp yarn on a first side of the corresponding flotation and pass under at least one adjacent warp yarn on a second side of the corresponding flotation. Furthermore, it is proposed that the weft yarns that are situated in the middle of any one of the floatations that define the diagonal twill lines each have one adjacent other weft yarn which other weft yarn passes over at least one adjacent warp yarn on the second side of the corresponding flotation and passes under at least one adjacent warp yarn on the first side of the corresponding flotation.

More preferably the weft yarns that are situated in the middle of any one of the floatations that define the diagonal twill lines pass over exactly one adjacent warp yarn on a first side of the corresponding flotation and pass under exactly two adjacent warp yarns on a second side of the corresponding flotation, wherein the weft yarns that are situated in the middle of any one of the floatations that define the diagonal twill lines each have one adjacent other weft yarn which other weft yarn passes over exactly one adjacent warp yarn on the second side of the corresponding flotation and passes under exactly two adjacent warp yarns on the first side of the corresponding flotation.

The weft yarns that are situated in the middle of any one of the floatations that define the diagonal twill lines and their corresponding adjacent other weft yarns can be equal to each other in view of at least one of the following features: cross section, material, type, but may differ from other weft yarns in the woven fabric in view of that feature. Especially the weft yarns of the pair of weft yarns can have a smaller diameter than other weft yarns of the woven fabric.

Other features which are considered as characteristic for the invention are set forth in the appended claims.

Although the invention is illustrated and described herein as embodied in a woven structured fabric with crossing twill lines, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof will be best understood from the following description of specific embodiments when read in connection with the accompanying drawings.

BRIEF DESCRIPTION OF THE FIGURES

FIG. 1 is a plan view of a prior art woven fabric;

FIGS. 2 and 2A show a first embodiment of a woven fabric, with FIG. 2 not forming part of the present invention and FIG. 2A representing a modification of the first embodiment which forms a part of the present invention;

FIGS. 3 and 3A show a second embodiment of a woven fabric, similar to the first embodiment, with FIG. 3 not forming part of the present invention and FIG. 3A representing a modification of the first embodiment which forms a part of the present invention;

FIGS. 4 and 4A show a third embodiment of a woven fabric, with FIG. 4 not forming part of the present invention and FIG. 4A representing a modification of the first embodiment which forms a part of the present invention;

FIGS. 5 and 5A show a fourth embodiment of a woven fabric, similar to the third embodiment, with FIG. 5 not forming part of the present invention and FIG. 5A representing a modification of the first embodiment which forms a part of the present invention;

FIGS. 6 and 6A show the weaving pattern and the weaving card of the embodiments of FIGS. 4 and 4A, respectively;

FIG. 7A-7F show the weft yarn paths of the embodiments of FIGS. 4 and 4A;

FIG. 8A-8C show the warp yarn paths of the embodiments of FIGS. 4 and 4A;

FIGS. 9 and 9A show a fifth embodiment of a woven fabric, similar to the third embodiment, with FIG. 9 not forming part of the present invention and FIG. 9A representing a modification of the first embodiment which forms a part of the present invention;

FIGS. 10 and 10A show a sixth embodiment of a woven fabric, with FIG. 10 not forming part of the present invention and FIG. 10A representing a modification of the first embodiment which forms a part of the present invention; and

FIGS. 11 and 12 show a seventh and an eighth embodiment, respectively, that do not form part of the present invention.

DETAILED DESCRIPTION OF THE INVENTION

Referring again to the figures of the drawing in detail, there is shown a first embodiment in FIG. 2 which does not form part of the present invention. FIG. 2 illustrates a view on the paper side of a portion of a woven fabric 10. The paper side is formed by a plurality of warp yarns interwoven with a plurality of weft yarns. Since the illustrated woven fabric 10 is a single layer fabric the same warp yarns and weft yarns also form the machine side of the woven fabric 10. For the sake of clarity only three warp yarns are provided with reference signs, namely WA1, WA2 and WA3, and only five weft yarns are provided with reference signs, namely WE1, WE2, WE3, WE4 and WE5. The fabric is flat woven which means that the warp yarns extend substantially, but not all necessarily exactly, in machine direction MD of the woven fabric 10, whereas the weft yarns extend in cross machine direction CD of the woven fabric 10. The woven

fabric 10 is made endless by a seam, which is not shown. In case the fabric is not flat woven but round woven the warp yarns would correspond to the weft yarns and vice versa.

Each warp yarn forms several floatations on the paper side of the woven fabric 10, wherein all floatations have the same length in the illustrated embodiment. One of these floatations is denominated with reference sign FL1 in FIG. 2. The floatation FL1 is formed by warp yarn WA1 which floats above the five weft yarns WE1-WE5. Another of these floatations is denominated with reference sign FL3 which is formed by warp yarn WA3 which also floats above the five weft yarns WE1-WE5. Yet another of these floatations is denominated with reference sign FL2 which is formed by warp yarn WA2 floating weft yarns WE1 and WE2 and three other weft yarns but not weft yarns WE3, WE4 or WE5. Flotation FL2 is directly neighboring both, floatation FL1 and floatation FL3, wherein the floatations FL1 and FL3 do not neighbor one another.

All the floatations together form a plurality of twill lines on the paper side of the woven fabric 10. In FIG. 2 some twill lines extend in a direction which—roughly speaking—extends from the lower right side to the upper left side. These twill lines will be referred to as “first diagonal twill lines” in the following. The remaining twill lines extend—again roughly speaking—in a direction from the lower left side to the upper right side in FIG. 2. These twill lines will be referred to as “second diagonal twill lines” in the following. The first diagonal twill lines are all parallel to each other and spaced apart from each other by the same distance. Similarly, the second diagonal twill lines are parallel to each other and spaced apart from each other. However the distance between the second twill lines varies in this exemplary embodiment. To be more precise, there are two different distances between parallel second twill lines, wherein the two different distances alternate.

Thus, the first diagonal twill lines and the second diagonal twill lines cross each other in a substantially regular pattern. The woven fabric 10 comprises areas with a plain weave structure between the intersecting first and second diagonal twill lines. These areas define pockets on the paper side of the woven fabric 10, whereas the first and second diagonal twill lines define elevations on the paper side of the woven fabric 10. Thus, the woven fabric 10 is structured on its paper side wherein the structure is preferably adapted to impart a good visible pattern on a final fiber web, in particular final tissue fiber web, that is formed or transported in a wet form on the paper side of the woven fabric 10.

For the sake of clarity only one first diagonal twill line is denominated with reference sign TL1 in FIG. 2, and only one second diagonal twill line is denominated with reference sign TL2 in FIG. 2. The floatation FL1 contributes to the definition of the first diagonal twill line TL1, the floatation FL3 contributes to the definition of the second diagonal twill line TL2, and the floatation FL2 contributes to the definition of both, the first and second diagonal twill lines TL1 and TL2. In other words, the floatation FL2 is situated at the crossing point of the two diagonal twill lines TL1 and TL2.

The first diagonal twill line TL1 forms a first angle with the machine direction MD of the woven fabric 10, which angle is not zero. The direction of the first diagonal twill line TL1 can be described by a first MD vector component MD-VC1 extending in the machine direction MD of the woven fabric 10 and a first CD vector component CD-VC1 extending in the cross machine direction CD of the woven fabric 10. The value of the first CD vector component CD-VC1 is unequal to zero.

The second diagonal twill line **TL2** forms a second angle with the machine direction **MD** of the woven fabric **10**, which angle is not zero. The direction of the second diagonal twill line **TL2** can be described by a second **MD** vector component **MD-VC2** extending in the machine direction **MD** of the woven fabric **10** and a second **CD** vector component **CD-VC2** extending in the cross machine direction **CD** of the woven fabric **10**. The value of the second **CD** vector component **CD-VC2** is unequal to zero.

Like in the present embodiment it is preferable that the first **MD** vector component **MD-VC1** is the same as the second **MD** vector component **MD-VC2** in view of its direction and magnitude, whereas the first **CD** vector component **CD-VC1** only corresponds to the second **CD** vector component **CD-VC2** in terms of its magnitude but not in terms of its direction. In fact, the first **CD** vector component **CD-VC1** is directed to the left in FIG. 2 and, thus, against the cross machine direction **CD** of the woven fabric **10**, whereas the second **CD** vector component **CD-VC2** is directed to the right in FIG. 2 and, thus, in cross machine direction **CD** of the woven fabric **10**. In other words the first **CD** vector component **CD-VC1** and the second **CD** vector component **CD-VC2** have the same absolute value but opposite signs. Here the sign of the first **CD** vector component **CD-VC1** is negative while the sign of the second **CD** vector component **CD-VC2** is positive.

The ratio of the first **MD** vector component **MD-VC1** and the first **CD** vector component **CD-VC1** is characteristic for the first angle formed by the first diagonal twill line **TL1** with the machine direction **MD** of the woven fabric **10**. The ratio of the second **MD** vector component **MD-VC1** and the second **CD** vector component **CD-VC2** is characteristic for the second angle formed by the second diagonal twill line **TL2** with the machine direction **MD** of the woven fabric **10**. The first angle and the second angle also have the same magnitude but opposite signs.

Such a woven fabric with corresponding first diagonal twill lines **TL1** and second diagonal twill lines **TL2** on its paper side is not only conducive to sheet building, especially when the sheet is transferred to it with a rush speed differential, but can also be easily guided on the paper machine.

Notably, the floatations **FL1** and **FL3** themselves are inclined with respect to the machine direction **MD** of the woven fabric **10**, wherein their inclination substantially corresponds to the inclination of the first diagonal twill line **TL1** and the second diagonal twill line **TL2** with the machine direction, respectively. In contrast to that, the flotation **FL2** at the crossing point of the two diagonal twill lines **TL1** and **TL2** extends substantially parallel to the machine direction **MD** of the woven fabric **10**.

FIG. 2A shows a modification of the first embodiment from FIG. 2 which modification forms part of the present invention. The portion of a woven fabric in FIG. 2A has substantially the same weaving pattern as the weaving pattern of the portion of the woven fabric **10** shown in FIG. 2. However, in FIG. 2A weft yarns with different diameters are applied. To be more precise, the weft yarns that pass under the middle of any of the floatations of the warp yarns on the paper side of the woven fabric have a smaller diameter than the remaining weft yarns that do not pass under the middle of any of the floatations of the warp yarns on the paper side of the woven fabric. The result of this is that the knuckles formed by the warp yarn floatations on the paper side are not as high and as pronounced as in the first embodiment according to FIG. 2. Thus, the pattern imparted in the final fiber web can be positively influenced.

In the modification according to FIG. 2A all warp yarn floatations on the paper side of the woven fabric have the same length because they all pass over five consecutive weft yarns. Furthermore, two consecutive weft yarns having a larger diameter are followed by one weft yarn having a smaller diameter and so on.

FIGS. 3 and 3A show a second embodiment not forming part of the present invention, similar to the first embodiment, and a modification of the second embodiment which forms part of the present invention, respectively. In the following only the differences as to the first embodiment and its modification will be explained. For the rest, reference is made to the above description.

The second embodiment according to FIG. 3 and its modification according to FIG. 3A substantially only differ from the first embodiment according to FIG. 2 and its modification according to FIG. 2A, respectively, in that some second twill lines are broader than the remaining second twill lines and also than the first twill lines. In fact, broad second twill lines alternate with small second twill lines. The width of the twill lines can be adjusted by the number of warp yarn floatations that contribute to their definition.

FIGS. 4 and 4A show a third embodiment not forming part of the present invention and a corresponding modification thereof which forms part of the present invention, respectively. In the following only the differences as to the first embodiment and its modification will be explained. For the rest, reference is made to the above description.

The third embodiment according to FIG. 4 and its modification according to FIG. 4A substantially differ from the first embodiment according to FIG. 2 and its modification according to FIG. 2A, respectively, in that some first twill lines end when reaching a second twill line and vice versa. In the portion of the woven fabric shown in FIG. 4 only one first diagonal twill line really crosses one second diagonal twill lines. All other first and second diagonal twill lines end at another diagonal twill line in this shown portion. The two crossing diagonal twill lines divide the shown portion of the woven fabric into four sections, two of them having first diagonal twill lines extending parallel to each other, and two of them having second diagonal twill lines extending parallel to each other.

The third embodiment according to FIG. 4 is described in more detail with respect to FIGS. 6-8C, wherein FIG. 6 shows the weaving pattern of the third embodiment, FIG. 6A shows the weaving card of the third embodiment, FIGS. 7A-7F show the weft yarn paths of the third embodiment, and FIGS. 8A-8C show the warp yarn paths of the third embodiment.

FIGS. 5 and 5A show a fourth embodiment not forming part of the present invention, similar to the third embodiment, and a modification of the second embodiment which forms part of the present invention, respectively. In the following only the differences as to the third embodiment and its modification will be explained. For the rest, reference is made to the above description.

The fourth embodiment according to FIG. 5 and its modification according to FIG. 5A substantially only differ from the third embodiment according to FIG. 4 and its modification according to FIG. 4A, respectively, in that some first and second twill lines are broader than the remaining first and second twill lines. In fact, broad first and second twill lines alternate with small first and second twill lines, respectively.

All exemplary embodiments one to four with their respective modifications have in common that the floatations which

form the diagonal twill lines each have a length of five. That means that the corresponding warp yarns pass over five consecutive weft yarns on the paper side of the woven fabric.

Furthermore, in all these embodiments one to four the weft yarns that pass under the middle of any of the floatations of the warp yarns on the paper side of the woven fabric are woven in a plain weave structure with the warp yarns of the woven fabric. Thus, each third weft yarn in these embodiments is woven in plain weave. In FIGS. 7A-f referring to the third embodiment these weft yarns correspond to weft yarns 3, 6, 9 and so on. Moreover, these weft yarns can be easily identified in FIGS. 2A, 3A, 4A and 5A referring to the corresponding modifications, since these weft yarns have a smaller diameter than the remaining weft yarns that do not pass under the middle of any of the floatations of the warp yarns on the paper side of the woven fabric.

Even though using weft yarns with a smaller diameter results in that the warp yarn floatations on the paper side are not as high as using weft yarns with a larger diameter, there is still room for improvements. It is the merit of the inventor to have found out that a weft yarn being up on either side at the center of every warp yarn flotation creates a pressure point at the center of each flotation which restricts fabric life. The pointed nature of the warp yarn flotation also makes it difficult to surface sand the fabric to the desired level of contact area without removing excessive amounts of material of the warp yarns. In addition, the weft yarns with the plain weave structure can make it difficult to drive the count high enough to reduce fabric permeability to a reasonable level.

To further improve the above-described embodiments of the present invention, it is proposed to substitute each weft yarn that passes under the middle of a flotation on the paper side of the woven fabric by a pair of adjacent weft yarns that are not woven in a plain weave structure. To be more precise, it is preferred that one weft yarn of the pair of weft yarns passes over exactly one warp yarn that is adjacent the flotation on a first side (e.g. on the left hand side) of the flotation and passes below exactly two warp yarns that are adjacent the flotation on a second side (e.g. on the right hand side) of the flotation, while the other weft yarn of the pair of weft yarns passes over exactly one warp yarn that is adjacent the flotation on the second side (e.g. the right hand side) of the flotation and passes below exactly two warp yarns that are adjacent the flotation on the first side (e.g. the left hand side) of that flotation.

Modifying that way the third embodiment shown in FIG. 4 and its corresponding modification shown in FIG. 4A results in the fifth embodiment shown in FIG. 9 and its corresponding modification shown in FIG. 9A, respectively. In the fifth embodiment and its modification each flotation of the warp yarns that form the diagonal twill lines has the length of seven, meaning that the corresponding warp yarns float over seven consecutive weft yarns on the paper side. Furthermore, each weft yarn from the pair of weft yarns passes over one warp yarn and then under three warp yarns instead of going up and down all the time as in the plain weave structure of the third embodiment. The result is that the woven fabric according to the fifth embodiment has the same number of weft knuckles compared to the third embodiment shown in FIG. 4 but the point at the center of the warp yarn flotation is flattened. The resulting fabric has much higher natural contact area so that less surface sanding is required to achieve the desired level of contact area. The pressure points are also eliminated. Furthermore, the elimination of the plain weave also allows the count to be woven

higher which gives the advantage of lower air permeabilities that leads to better sheet drying.

A sixth embodiment, which does not form a part of the present invention, is shown in FIG. 10. Like in the fifth embodiment the warp yarn floatations forming the diagonal twill lines all have the length of seven. Furthermore, weft yarns that are situated in the middle of any one of the floatations that define the diagonal twill lines pass over exactly one adjacent warp yarn on a first side of the corresponding flotation and pass under exactly two adjacent warp yarns on a second side of the corresponding flotation, wherein the weft yarns that are situated in the middle of any one of the floatations that define the diagonal twill lines each have one adjacent other weft yarn which other weft yarn passes over exactly one adjacent warp yarn on the second side of the corresponding flotation and passes under exactly two adjacent warp yarns on the first side of the corresponding flotation. Thus, this embodiment substantially exhibits the same advantageous like the previously described fifth embodiment.

FIG. 10A shows a modification of the sixth embodiment from FIG. 10, which modification forms part of the present invention. The portion of a woven fabric in FIG. 10A has substantially the same weaving pattern as the weaving pattern of the portion of the woven fabric shown in FIG. 10. However, in FIG. 10A weft yarns with different diameter are applied. To be more precise, the weft yarns that are situated in the middle of any one of the floatations that define the diagonal twill lines and their corresponding adjacent other weft yarns have a smaller diameter than the remaining weft yarns that do not pass under the middle of any of the floatations of the warp yarns on the paper side of the woven fabric. This results in that the knuckles formed by the warp yarn floatations on the paper side are even less high compared in the sixth embodiment according to FIG. 10.

A seventh and an eighth exemplary embodiment, neither or them forming a part of the present invention, are shown in FIGS. 11 and 12 respectively. In contrast with the previously described embodiments, the floatations that form the diagonal twill lines have a length greater than 7, which means that the corresponding warp yarns pass over more than 7 consecutive weft yarns. Furthermore, in these two embodiments the twill lines do not cross each other. Last but not least, the weft yarns of the seventh embodiment according to FIG. 11 all have the same weaving pattern, meaning here that all weft yarns pass over one warp yarn and then under seven warp yarns on the paper side of the fabric.

Many further modifications are thinkable within the scope and spirit of the present invention as defined in the independent claims.

Finally it should be noted that the modified embodiments according to the present invention shown in FIGS. 2A, 3A, 4A, 5A, 9A and 10A may additionally differ from their corresponding basic embodiments according to FIGS. 2, 3, 4, 5, 9 and 10, respectively, in that some weft yarns are made from another material and/or are of a different type than other weft yarns.

Once more in an abstract summary: The invention concerns a woven fabric (10) for use in a machine to produce a fiber web, preferably a tissue fiber web, the woven fabric (10) having a machine direction (MD) and a cross machine direction (CD), as well as a paper side and a machine side, wherein the paper side is formed by warp yarns (WA1-WA3) and by weft yarns (WE1-WE5) which warp yarns (WA1-WA3) and weft yarns (WE1-WE5) are interwoven with each other, wherein the paper side comprises a plurality of twill lines (TL1, TL2), each twill line (TL1, TL2) being formed

11

by a plurality of neighboring floatations (FL1-FL3) of warp yarns (WA1-WA3), wherein the twill lines (TL1, TL2) comprise an MD vector component (MD-VC1, MD-VC2) directed in the machine direction (MD) of the woven fabric (10) and a CD vector component (CD-VC1, CD-VC2) directed in the cross machine direction (CD) of the woven fabric (10), and wherein at least some twill lines (TL1, TL2) are diagonal twill lines (TL1, TL2) meaning that the CD vector component (CD-VC1, CD-VC2) of these twill lines (TL1, TL2) is unequal to zero. The plurality of diagonal twill lines (TL1, TL2) consists of first diagonal twill lines (TL1) and second diagonal twill lines (TL2), wherein the CD vector components (CD-VC1) of the first diagonal twill lines (TL1) have an opposite sign to the CD vector components (CD-VC2) of the second diagonal twill lines (TL2), and wherein the sum of all CD vector components (CD-VC1) of the first diagonal twill lines (TL1) is substantially balanced with the sum of all CD vector components (CD-VC2) of the second diagonal twill lines (TL2).

The following is a summary list of reference numerals and the corresponding structure used in the above description of the invention:

- 10 woven fabric
- 10' woven fabric (prior art)
- CD cross machine direction
- CD-VC1 first CD vector component
- CD-VC2 second CD vector component
- CD-VC' CD vector component (prior art)
- FL1-FL3 floatations
- FL' flotation (prior art)
- MD machine direction
- MD-VC1 first MD vector component
- MD-VC2 second MD vector component
- MD-VC' MD vector component (prior art)
- TL1 first diagonal twill line
- TL2 second diagonal twill line
- TL' twill line (prior art)
- WA1-WA3 warp yarns
- WA1'-WA3' warp yarns (prior art)
- WE1-WE5 weft yarns
- WE1'-WE5' weft yarns (prior art)

The invention claimed is:

1. A woven fabric for use in a machine for producing a fiber web, the woven fabric, the woven fabric comprising: a multiplicity of mutually interwoven warp yarns and weft yarns forming a paper side of the woven fabric; said paper side having a plurality of twill lines each being formed by a plurality of neighboring floatations of said warp yarns; said twill lines having an MD vector component directed in a machine direction (MD) of the woven fabric and a CD vector component directed in a cross machine direction (CD) of the woven fabric; at least some of said twill lines being diagonal twill lines having a CD vector component that is unequal to zero; a plurality of said diagonal twill lines consisting of first diagonal twill lines and second diagonal twill lines, wherein the CD vector components of the first diagonal twill lines have an opposite sign to the CD vector components of the second diagonal twill lines;

12

a sum of all CD vector components of said first diagonal twill lines being substantially balanced with a sum of all CD vector components of said second diagonal twill lines;

5 said weft yarns that are located in a middle of any one of said floatations that define said diagonal twill lines having a cross section which is smaller than a cross sections of the remaining said weft yarns that are not located in the middle of any one of said floatations that define said diagonal twill lines.

10 2. The woven fabric according to claim 1, wherein a number of said first diagonal twill lines is substantially equal to a number of said second diagonal twill lines.

15 3. The woven fabric according to claim 1, wherein a total length of all first diagonal twill lines is substantially equal to a total length of all second diagonal twill lines.

20 4. The woven fabric according to claim 1, wherein all of said first diagonal twill lines have the same first CD vector component and all of said second diagonal twill lines have the same second CD vector component.

25 5. The woven fabric according to claim 4, wherein an absolute value of said first CD vector component is equal to an absolute value of said second CD vector component.

6. The woven fabric according to claim 1, wherein all diagonal twill lines have the same MD vector component.

7. The woven fabric according to claim 1, wherein said diagonal twill lines are formed from neighboring floatations of warp yarns, and wherein the floatations have a length of at least 3.

30 8. The woven fabric according to claim 1, wherein said diagonal twill lines are formed from neighboring floatations of warp yarns, and wherein the floatations have a length of 5.

9. The woven fabric according to claim 1, wherein some of said weft yarns differ from other said weft yarns in at least one feature selected from the group consisting of a cross section, a material, and a type of yarn.

40 10. The woven fabric according to claim 1, wherein said diagonal twill lines are formed from neighboring floatations of warp yarns, and said warp yarns that form said diagonal twill lines are interwoven with said weft yarns in a plain weave structure between successive said floatations.

11. The woven fabric according to claim 1, wherein said diagonal twill lines are formed from floatations of said warp yarns and said floatations of said warp yarns which define the diagonal twill lines themselves enclose an angle unequal to 0° with the machine direction of the woven fabric, and wherein a sign of the angle corresponds to a sign of said MD vector component of said diagonal twill line that is formed by the corresponding flotation.

45 12. The woven fabric according to claim 1, wherein at least some of said diagonal twill lines extend straight from one side of the woven fabric to an opposite side thereof.

13. The woven fabric according to claim 1, wherein at least some of said diagonal twill lines end somewhere between opposite sides of the woven fabric.

50 14. The woven fabric according to claim 1, wherein some of said diagonal twill lines are broader than other said diagonal twill lines.
